DESK TELEPHONE APPARATUS FOR INTER-COMMUNICATION SYSTEMS

Rune Gotthard Monö, Roslags-Nasby, Sweden, assignor to Aktiebolaget Gylling & Co., Stockholm-Grondal, Sweden

Filed Dec. 31, 1959, Ser. No. 58,866

Claims priority, application Norway Sept. 10, 1959

Term of patent 14 years

(Cl. D26—14)

FIG. 1

FIG. 2

FIG. 3

FIG. 4

Fig. 1 is a perspective view of a desk telephone apparatus for intercommunication systems, showing my new design;

Fig. 2 is a side elevational view, the opposite side being substantially a mirror image thereof;

Fig. 3 is a front elevational view thereof; and

Fig. 4 is a rear elevational view thereof.

I claim:

The ornamental design for a desk telephone apparatus for intercommunication systems, as shown.
